Primary Examiner — Natasha Vujcic(74) *Attorney, Agent, or Firm* — HAUPTMAN HAM, LLP(57) **CLAIM**

The ornamental design for an outdoor unit for air conditioner as shown and described.

DESCRIPTION

FIG. 1 is a perspective view of an outdoor unit for air conditioner showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken lines depict portions of the outdoor unit for air conditioner that form no part of claimed design.
